DESIGN FOR A TABLE FORK

John Klaus, Boulder, Colo.

Application February 26, 1940, Serial No. 90,533

Term of patent 3½ years

To all whom it may concern:

Be it known that I, John Klaus, a citizen of the United States, residing at Boulder, in the county of Boulder and State of Colorado, have invented a new, original, and ornamental Design for a Table Fork, of which the following is a specification, reference being had to the accompanying drawing, forming part thereof.

In the drawing:

Fig. 1 is a perspective view of a table fork showing my new design; and

Fig. 2 is a longitudinal fragmentary view there-

of, taken on the line 2—2, Fig. 1, a portion of the handle being broken away for convenience of illustration.

My design for a table fork is characterized by the relatively flat bottomed grooves in the back of the heel of the fork between each line which combine with the curve of the heel to form relatively long, rounded, parallel indentations.

I claim:

The ornamental design for a table fork, as shown and described.

JOHN KLAUS.
